UNITED STATES PATENT OFFICE.

WILLIAM JAMES, OF ADELAIDE, SOUTH AUSTRALIA.

HARNESS-MACHINE.

SPECIFICATION forming part of Letters Patent No. 443,679, dated December 30, 1890.

Application filed September 13, 1890. Serial No. 364,848. (No model.)

To all whom it may concern:

Be it known that I, WILLIAM JAMES, of 5 Adelaide, South Australia, have invented a new and useful Improvement in Machines for Working Leather, &c., of which the following is a specification.

My invention relates to an improvement in combination-machines for working leather and other materials in which a vertically-adjustable yoke is adapted to receive interchangeable tools, which, in connection with a suitable support, serve to operate upon the leather in the desired manner.

My invention also provides for working 15 upon the edges of broad sheets of material and at the same time forming a rigid frame for working upon narrower strips where a considerable portion of the surface and one or both edges may be subjected to the action of 20 the tools.

A practical embodiment of my invention is represented in the accompanying drawings, in which—

Figure 1 represents a front view of the machine, showing in connection therewith a rotary spindle carrying pricking-wheels for indicating both straight and sinuous lines of stitching. Fig. 2 is a transverse vertical section from front to rear. Fig. 3 is a view in 25 detail of the guide, and showing its connection with the frame. Fig. 4 is a view in side elevation in detail of a cam-support for purposes of skiving and splitting. Fig. 5 is an end view of the same. Fig. 6 is a view in detail of a 30 roller for supporting different widths of straps or strips of material, the edges of which are intended to be operated upon. Fig. 7 is a side view in detail of the oval pricking-wheel.

The main frame of the machine consists of 40 a base portion A, from one end of which a short upright portion a extends, and from the opposite end of which an upright portion a' extends upwardly, thence laterally, as shown at a², and thence downwardly, as shown at a³, 45 to a point a short distance above the short upright portion a. The inner faces of the upright portions a' and a³ are provided with longitudinally-extending grooves B, which terminate at their lower ends, one at the opening 50 between the parts a and a³ of the frame and the other in a recess b, which extends inwardly from the front of the upright portion

a'. The opening between the parts a and a³ and the recess b are intended to be of such width as to receive therein the squared ends 5: of bearings C of the interchangeable spindles which support the various tools. The grooves B in the inner faces of the portions a' and a³ of the frame are also intended to correspond to the said squared portions C of the bearings, and to receive them with an easy sliding fit when they have been inserted within the opening upon one side and the recess b upon the other side in position beneath the lower end of the grooves. 65

Between the inner faces of the portions a' and a³ there is located a yoke D, the ends of which are turned downwardly and rest with their outer faces in close sliding contact with said inner faces of the frame. The downwardly-turned ends of said yoke are provided with recesses d, which open toward the front edges of the ends, and which are adapted to receive the squared ends C of the tool-holding spindles when the latter are slid rearwardly 75 into position to be received within the grooves B. The yoke D is connected at its middle portion with an adjusting-screw E, provided with a hand-wheel e, said adjusting-screw being seated in a threaded socket formed in the top portion a² of the frame and having its lower end connected with the yoke so as to turn freely, but at the same time locked to the yoke so as to cause the yoke to rise and fall as the screw is turned up or down within 80 its threaded socket of the frame. In the present instance I have shown the lower end of the screw provided with a disk portion e', from the lower face of which projects a reduced cylindrical portion e². The reduced 85 portion e² extends through and works freely in a socket formed in the yoke, and is provided at its lower end beneath the yoke with a disk e³, which is fixed to the reduced portion e², so as to prevent it from being withdrawn from the socket in the yoke, thereby 90 causing the yoke to follow the up and down movements of the screw. 95

As supports for the work to be operated upon, I provide interchangeable rollers, three 100 examples of which are represented in the accompanying drawings. In Fig. 1 I have shown a cylindrical roller F, loosely mounted upon a removable spindle G, seated in suit-

able bearings formed in the upright portions *a* and *a'* of the main frame and conveniently provided with a handle *g* for withdrawing it from the frame and from the roller *F*, through 5 which it extends, and thereby allowing the ready removal of the roller for the purpose of inserting one of another form.

For the purpose of guiding the material to be operated upon truly beneath the operating tools, I have provided the back of the frame with a supporting-arm *H*, extending laterally across the opening between the uprights *a* and *a'* of the frame and provided at one end with a vertically-elongated slot *h* for the purpose of adjusting the arm up and down to bring its upper surface into the proper relation to the surface of the roller or work-support in use. The said arm *H* is adjusted and supported by means of a headed stud *h'*, 20 which projects rearwardly from the main frame, and is adapted to be received through the wider portion of the slot *h*, and when so inserted and the arm slid upwardly for a slight distance the sides of the head of the 25 stud *h'* will engage the said arm at the opposite edges of the slot and prevent it from outward displacement. In addition to the stud *h'*, a binding-screw *h*² is inserted through the slot into the frame and serves, together with 30 the stud *h'*, to lock the arm in the desired adjustment. Upon the arm *H* a pair of guide-cheeks *I* are located and adapted to slide. The said cheeks are locked in any desired 35 position upon the arm by means of binding-screws *i*.

When it is desired to work upon the edge of a broad sheet of leather or other material, the space between the portions *a* and *a'* of the main frame is left open, and through this 40 the material may be passed while its edge is engaged by the tools. When, however, it is desired to do fine work simultaneously upon the opposite edges of narrow strips or throughout a great extent of the width of the strip, 45 it is desirable that the portion of the frame supporting the cutting-tool should not be allowed to spring back from its work at either edge. To prevent this I provide a brace *K*, pivotally secured at its lower end to the outer 50 edge portion *a* of the main frame, preferably by means of a screw *k*, and at its upper end provided with a binding-screw *k'*, which, when the brace is swung into position, is adapted to engage a threaded perforation in 55 the outer edge of the portion *a'* of the main frame, and thereby secure the brace in position, connecting the portions *a* and *a'* of the frame, wholly preventing any tendency of the frame to yield at that end of the spindle 60 or at that edge of the material being operated upon.

In Fig. 1 I have shown a rotary spindle *L*, squared for the purpose of preventing the rotary movement of the tools supported thereon, and provided with a screw-thread at its 65 corners for the purpose of operating adjusting-nuts *l* thereon to hold the tools in posi-

tion. The said spindle is here shown as provided with a pair of pricking-wheels *l'*, adjusted the desired distance apart for indicating the position of parallel seams, and also a pricking-wheel *l*² of oblong shape, secured in an oblique position upon the spindle by means of a pair of oblique-faced cheeks *l*³. The spindle is also shown as provided with a 75 crank *M*, having a handle *m* for rotating it.

In Fig. 4 I have represented a cam-roller *F'*, which may be utilized both for skiving and for splitting leather or other strips of material.

In Fig. 6 I have shown a roller provided with annular recesses of various widths for the purpose of thinning the edges of leather or other material.

The spindles carrying the work-tools are 85 adjusted in the frame by lowering the yoke to a position such that the recesses in its ends will correspond with the recess *b* in the frame and the opening between the parts *a* *a'*, and then inserting the squared ends of the spindle or spindle-bearing rearwardly into the recesses in the yoke, and then, by means of the screw *E*, elevating the yoke, thereby drawing the said squared ends *C* of the spindle upwardly into the grooves *B* of the main frame. 90 In this position the spindle is securely locked against both lateral and vertical displacement, and may be adjusted vertically at pleasure by means of the screw *E*.

For the purpose of giving the roller or work-support a yielding adjustment when the class of work performed—as, for example, trimming—demands it, I provide a spring-cushion, upon which the roller-spindle may be supported. In the present instance this is 105 represented as a stem *O*, provided with a nut *o* for adjusting it vertically, the said stem having two spring-arms *o'* branching therefrom, the ends of the arms resting in position to engage the under side of a bar *o*², having 110 standards to engage the ends of the roller-spindle when it rests in its bearings. The roller spindle-bearings are for this purpose elongated vertically.

What I claim as my invention is—

1. The combination, with a frame consisting of upright portions provided with grooves in the opposite inner faces and with openings from the side of the frame to said grooves, a tool-holding-spindle, and a tool, of a yoke provided with recesses for the reception of the tool-holding spindle, said recesses in the yoke corresponding with the grooves in the frame, means for adjusting the yoke longitudinally of the grooves in the frame, and a removable support for interchangeable rollers or work-supports seated in the frame, substantially as set forth.

2. The combination, with a frame consisting of a portion extending upward, laterally, and downward and permanently connected with the base at one end only, the said frame being provided with grooves in the opposite faces of its upwardly and downwardly extend-

ing portions for the reception of a tool-holding spindle, of the tool-holding spindle and tool, and an adjustable brace for connecting the free end of said frame rigidly with the 5 base or releasing it therefrom, the opening across which the said brace is arranged to extend being located in position to receive the material to be operated upon while traveling in engagement with the tool, substantially as set forth.

3. The combination, with the frame provided with a seat for the tool-holding spindle, the tool-holding spindle, and interchangeable tools adapted to the spindle, of a removable 15 support for interchangeable rollers or work-supports, a guide-supporting arm secured to the main frame in vertical adjustment to correspond with the varying positions of the surface of the work-supports, and laterally-ad-

justable cheeks secured on the arm to guide 20 the work to suit the interchangeable tools, substantially as set forth.

4. The combination, with the frame and the vertically-adjustable yoke, of the spindle seated in the frame and yoke, an oval-shaped 25 pricking-wheel secured in an oblique position upon the spindle, and the work-support, substantially as set forth.

5. The combination, with the frame and the spindle-support, of a squared spindle for receiving the tools, and said tools, the corners of the spindle being screw-threaded, and adjusting-nuts working in the spindle to adjust the tools, substantially as set forth.

WILLIAM JAMES.
